UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

LAMP-SOCKET.

987,690.

Specification of Letters Patent. Patented Mar. 28, 1911.

Application filed April 11, 1907. Serial No. 367,658.

To all whom it may concern:

Be it known that I, REUBEN B. BENJAMIN, a citizen of the United States, residing at Chicago, in the county of Cook and State of Illinois, have invented new and useful Improvements in Lamp-Sockets, of which the following is a full, clear, concise, and exact description, reference being had to the accompanying drawing, forming a part of this specification.

This invention relates to improvements in incandescent electric lamp sockets, and particularly to a type of such socket which is adapted to carry a plurality of lamps with their axes disposed in a common plane.

One of the objects of this invention is the provision of a device of this class in which all of the current-carrying parts are protected from the access of moisture thereto.

Another object of the invention is to provide such a device wherein means are provided whereby connection may be readily made with supply wires leading to the device, these means being concealed from view and protected from the weather.

In the drawings accompanying this specification, I have shown my invention embodied in various devices containing the principal features of my invention.

In these drawings Figure 1 is a central vertical sectional view of a form of device embodying my invention, the section being taken on the line 1—1 of Fig. 3; Fig. 2 is a top plan view of the same; Fig. 3 is an elevational view of the same looking into one of the lamp-receiving sockets; Fig. 4 is a central vertical sectional view of the same, the section being taken on the line 4—4 of Fig. 1, looking in the direction indicated by the arrows; Fig. 5 is a broken elevational view of this form of the device, looking at the side opposite that seen in Fig. 3; Fig. 6 is a broken sectional view, the section being taken on the line 6—6 of Fig. 3, looking in the direction indicated by the arrows; Fig. 7 is a sectional view similar to Fig. 1 but showing a slightly different form of the device, the section being taken on the line 7—7 of Fig. 8; Fig. 8 is an elevational view similar to Fig. 3 but showing the form of device illustrated in Fig. 7; Fig. 9 is a top plan

view of this form of the device; Fig. 10 is a sectional view, the section being taken on the line 10—10 of Fig. 7, looking in the direction indicated by the arrows; and Fig. 11 is a broken elevational view of a further modified form of the device.

Referring particularly to Figs. 1 to 6 inclusive, 12 is a hollow shell, formed preferably of sheet metal and having one of its ends expanded at 13 to form a circular cup-shaped chamber and its edge outwardly flanged at 14 to provide a supporting base for securing the device to a plane surface. This flanged portion 14 is provided with suitable openings 15 for the reception of screws or the like for securing the device in place. At the opposite end of the shell 12 is a cylindrical shell 16 which may be formed of the same material as the member 12, and secured thereto in any convenient or preferred manner, but preferably by forming the shell 16 with an opening in its side into which is inserted the end of the shell 12, the material of this shell 12 being then flanged outwardly so as to clench the same in place in the opening in the shell 16. By this means a rigid and practically integral structure is provided.

The sheet metal members 12 and 16 are coated on one side, or preferably on both sides, with a layer of enamel 17, this enamel being put on after the parts 12 and 16 have been secured together. This enamel coating serves to prevent moisture from finding its way into the device through the joints between the parts, as well as providing a complete insulating coating for these parts.

Arranged within the shell 16 is a base 18, formed of porcelain or other suitable non-conducting material. This base 18 is substantially disk-shaped and has secured to its opposite faces suitable lamp-receiving shells and lamp-terminal-engaging contacts associated with said shells. These shells 19 and 20 are secured in place on the base 18 by a pair of bolts 21—21 which extend through the base 18 from one of these shells to the other. The base 18 is formed with a groove 22 extending across the base, and in this groove 22 lies a contact plate 23. This plate 23 has its ends bent at a right angle with the main

body portion thereof and parallel with each other, and a bolt 24 extends centrally through the base 18 and through the ends of the plate 23. The ends of this bolt 24 serve as the center contacts for engagement with the center terminals of lamps when the same are inserted into the sockets 19 and 20.

Resting within the chamber formed in the upper expanded portion of the member 12 is an insulating and preferably circular block 25, this block 25 being provided with channels 26 and 27 in which the leading-in wires are adapted to lie when such wires are connected with the device. Extending through the insulating block 25 and passing longitudinally through the hollow member 12 are a pair of bolts 28 and 29, the heads of these bolts resting in the channels 26 and 27 in the block 25. The bolt 28 is screw-threaded upon its inner end and takes into a suitably screw-threaded opening in the plate 23 which serves to conduct current to the center contacts of the device, as above described. A plate 30 is arranged in the channel 26 and is provided with a binding-screw 31 and serves to conduct current from this binding-screw to the head of the bolt 28, which passes therethrough. The bolt 29 is similarly screw-threaded upon its inner end and takes into a screw-threaded opening in a plate 32, this plate being disposed in a groove 33 provided in the base 18 and having its ends bent downward and lying between the base 18 and the sockets 19 and 20, thereby electrically connecting these sockets with the bolt 29. A conducting plate 34 and binding-screws 35 are arranged in the channel 27 for making electrical connection with the bolt 29.

To prevent the base 18 from rotating in the shell 16 when lamps are screwed into the sockets 19 and 20 I provide an insulating spacing block in the form of a disk 36 in the shell 12, this disk 36 having suitable openings through which pass the bolts 28 and 29. These bolts are thus prevented from coming in contact with the interior of the casing 12. To prevent the block 36 from working up away from the base 18 I provide a spring 37 which is sleeved on the bolt 29 and bears at one end against the block 36, the opposite end of this spring 37 being seated against a nut 38 on the bolt 29.

It will be seen that in the device hereinabove described I have provided a lamp-holding device in which a plurality of lamps are arranged with their axes extending in the same plane and parallel with a plane surface to which the device is secured, and that the means for making electrical connection with the source of supply of electric current are concealed from view behind the plane surface of the support. The block

25 is preferably circular in form so as to pass readily into a circular opening in the wall to which the device is secured. This is of importance when the device is used in exposed positions such as upon the wall or shell of a hollow sign or in any other similarly exposed position.

Referring now to Figs. 7, 8, 9 and 10, 39 is a hollow cylindrical shell formed preferably of sheet metal and having secured upon one of its ends a hollow shell 40. This shell 40 contains the lamp-receiving sockets and associated contacts. Upon the other end of the shell 39 is secured a dish-shaped part 41 of sheet metal or the like, this part 41 being provided with an opening into which fits the end of the member 39. These members 39 and 41 are secured together by flanging the end of the member 39 outward so as to lock over the edge of the opening in the member 41. The member 41 is provided with an outwardly extending flange 42 having openings 43 for screws or the like for securing the device to a plane surface. An insulating block 44 rests within the hollow of the member 41 and is provided upon its upper side with channels 45 and 46. A pair of bolts 47 and 48 extend through the block 44 and pass longitudinally through the chamber within the member 39. The bolt 47 extends through an opening 49 in the base 50 and is screwed into a plate 51, this plate lying in a passage 52 which extends transversely through the base 50. This plate 51 has its opposite ends bent at a right angle with the main body of the plate and parallel with each other, these ends constituting the center contacts for the device. The sockets 53 and 54 are secured to the base 50 and are electrically connected with each other by means of a pair of bolts 55—55 which pass transversely through the base 50. The bolt 48 extends through the block 44 and part 39 and is screwed into a plate 56, this plate resting in a groove 57 formed in the base 50, and having its ends bent at a right angle with its main body portion and engaging with the sockets 53 and 54 and making electrical connection between the bolt 48 and the sockets. In the channels 45 and 46 on the block 44 are arranged a pair of conducting plates 58 and 59, these plates being provided with binding screws 60 and 61. The bolts 47 and 48 pass through these plates 58 and 59, and when supply wires are connected with the binding-screws 60 and 61 electrical connection is thus made through these bolts with the sockets and the contacts thereof. Within the casing 40, and insulating this casing from the sockets 53 and 54, is an insulating shell 62, formed of fiber or the like and preferably extending beyond the part 40 at each end thereof. In

this form of the device the insulating coating of enamel is omitted, being unnecessary when the device is to be used in unexposed situations.

5 Fig. 11 is a broken elevational view of a form of device which is adapted to receive a pair of soft rubber rings 63—63. These rings are designed to exclude moisture from the sockets and other conducting parts of 10 the device by closing the opening which would otherwise be left between the lamp 64 and the edge of the lamp-receiving shell. These rings 63 are slightly compressed when the lamp is screwed into place.

15 Having thus described my invention, what I claim as new and desire to secure by Letters Patent is—

1. In a lamp-holding device, the combination of a cylindrical shell, a lamp-receiving 20 socket arranged therein, a tubular stem extending from the side of said shell, and having its outer end expanded to form a supporting base, an insulating base in said stem, binding terminals on said insulating 25 base, contacts associated with said socket, and means extending through said stem for electrically connecting said binding terminals to said socket contacts.

2. In a lamp-holding device, the combination of a shell, a lamp-receiving socket in 30 said shell, a tubular supporting stem secured at one of its ends to said shell and having its opposite end expanded to form a chamber, an insulating base in said chamber, binding 35 screws on said base, contacts associated with said socket, and means extending through said stem for electrically connecting said binding terminals with said socket contacts.

3. In a lamp-holding device, the combination of a shell, a lamp-receiving socket in 40 said shell, contacts for said socket, a tubular supporting stem extending from said shell and expanded to form a chamber in said stem remote from said socket, an insulating 45 member in said chamber, binding terminals on said member, and means located within said stem, extending from said binding terminals to the contacts of the socket and electrically connecting the same.

50 4. In a lamp-holding device, the combination of a tubular metallic shell carrying lamp-receiving sockets, a tubular metallic stem secured at one of its ends to said shell at right angles therewith, and having its 55 opposite end expanded to form a chamber and further expanded to form a supporting base, an insulating block arranged within said chamber and carrying means for the attachment of supply wires, and means extending through said stem for conducting current to the contacts of said sockets.

60 5. In a lamp-holding device, the combination of a tubular casing carrying a pair of

lamp-receiving shells, a hollow stem secured at one of its ends to said casing and having 65 its opposite end expanded to form a chamber and further expanded to form a supporting base for said device, and an insulating block arranged in said chamber and being of greater thickness than the depth of said 70 chamber, said block being provided with channels extending therethrough for containing supply wires.

6. In a lamp-holding device, the combination of a cylindrical shell containing a pair 75 of lamp-receiving sockets, and a tubular stem having one of its ends secured to said shell and its opposite end expanded to form a supporting base for the device, said shell and stem being provided with a coating of impervious material adapted to exclude moisture from the joints of said device and to provide an insulating covering for said parts.

7. In a lamp-holding device, the combination of a tubular shell having lamp-receiving 80 sockets arranged therein, a tubular stem extending at a right angle with said shell and secured at one of its ends to said shell, the opposite end of said stem being expanded to form a base, suitable contacts associated with said sockets, and means for conducting current to said sockets, said shell and stem being provided exteriorly and interiorly with a coating of impervious and insulating material for excluding moisture from the joints 85 between the parts of said device and providing insulation for the same.

8. In a lamp-holding device, the combination of a continuous cylindrical tube having a lamp-receiving socket in each of its ends, 90 a tubular stem extending from the side of said tube and having its outer end expanded to form a supporting base, an insulating base in said stem, binding-screws on said insulating base, contacts associated with said sockets, and means extending through said stem for conducting current from said binding-screws to said sockets.

9. In a lamp-holding device, the combination of a tubular shell having an insulating 95 base arranged therein midway between its ends, a lamp-receiving socket secured to each side of said base, a supporting stem extending from the side of said tubular shell and provided with an expanded end for securing the device to a support, and means extending through said stem and adapted to conduct current to said contacts.

10. In a lamp-holding device, the combination of a metallic shell circular in cross-section, said shell being expanded to form a chamber near one end thereof and having its edge further expanded to form a supporting base, an insulating base disposed within said chamber and carrying binding-screws, 120 125 a second metallic shell arranged at right

angles with said first-named shell, lamp-receiving sockets in said last-named shell, contacts associated therewith, and means for conducting current from the binding-screws to said contacts, said second-named shell being interiorly coated with insulating material.

In witness whereof, I have hereunto subscribed my name in the presence of two witnesses.

REUBEN B. BENJAMIN.
